AUTOMATIC COUPLING

Application filed October 3, 1927. Serial No. 223,535.

This invention relates to automatic couplings of the type employed on railway cars for connecting fluid pressure carrying train lines between the cars of a train.

5 With certain types of automatic train line connectors, the connector is carried by the car coupling or draw-bar and is subject to a spring resistance of such force as required to ensure that the connectors will properly couple and at the same time provide for a yielding movement of the connector to accommodate and permit relative longitudinal movement of the car couplers. With a spring resistance of sufficient force to ensure the 10 coupling up of the connectors, the pressure of the spring acting after the cars are coupled tends to interfere with the proper action of the car coupler.

The principal object of my invention is to 20 provide an automatic fluid pressure train line connector having means by which a force is exerted sufficient to ensure the coupling of the connectors, but adapted to exert a reduced pressure after the cars are coupled.

25 In the accompanying drawing, the single figure is a view of a car coupler having an automatic train line connector associated therewith and showing my invention applied thereto.

30 In the drawing, the reference numeral 1 indicates the usual car coupler having the usual coupler shank 2. Secured to the car coupler is a yoke 3 in which an automatic train line connector 4 is supported and is 35 adapted to slide longitudinally. The connector 4 is provided with a rearwardly extending bar or stem 5 which slidably extends through an opening in a bracket 6, which bracket is secured to the coupler shank 2.

40 Interposed between the rear end of the connector 4 and the bracket 6 and surrounding the stem 5 is a coil spring 7 which is adapted to yieldingly resist relative movement of the connector 4 with respect to the 45 car coupler 1.

Rigid with the car body is a bracket 8, which can also be the yoke supporting the coupler shank 2, and having a cylindrical chamber 9 opening at its lower end and containing a member 10 on which is pivotally

55 mounted a roller 11. The member 10 has a chamber 12 and contains a coil spring 13 which urges the member 10 downwardly. A cam face 14 is provided on the upper side of the connector 4 and the roller 11 is adapted to engage said cam face when the parts are in the uncoupled position, as shown in the drawing.

60 The train pipe connector 4 is so positioned relatively to the car coupler 1, that when two cars are brought together for coupling up, the connectors 4 of the two cars will engage before the car couplers 1 engage and as the cars move together, movement of the connector 4 on each car is resisted by the 65 pressure of the spring 13 holding the roller 11 in engagement with the cam face 14. The resistance to rearward movement of the connector 4 thus set up is sufficient to ensure the 70 coupling movement of the counterpart connectors 4. After the connectors 4 have been coupled, further movement of the two cars toward each other causes the rollers 11 to ride up over the cam faces 14, so as to relieve the connectors of the resistance to movement as set up by the engagement of the 75 rollers 11 with the cam faces 14.

76 The movement of the connectors is then resisted only by the pressure of the springs 7 which are relatively of light resistance. 80 The car couplers 1 then couple up and after the car couplers are coupled, relative movement between the car couplers is only resisted by the force exerted by the light springs 7, which need only be of sufficient force to ensure 85 movement of the connectors 4 to normal position, when cars are uncoupled.

86 While one illustrative embodiment of the invention has been described in detail, it is not my intention to limit its scope to that embodiment or otherwise than by the terms of the appended claims.

87 Having now described my invention, what I claim as new and desire to secure by Letters Patent, is:—

90 1. The combination with a fluid pressure train line connector adapted to automatically couple with a counterpart connector upon the coming together of two cars, of a resist- 95 100

ance device laterally movable and longitudinally rigid with respect to the connector and disposed in the path of rearward movement of said connector for resisting movement of the connector in the act of coupling with a counterpart connector, said device being moved out of the path of said connector upon a predetermined increase in the force applied to move said connector rearwardly for automatically relieving the connector of the resisting force of said device after counterpart connectors are coupled up.

2. The combination with a fluid pressure train line connector adapted to automatically couple with a counterpart connector upon the coming together of two cars, of a resistance device laterally movable and longitudinally rigid with respect to the connector for opposing rearward longitudinal movement of the connector in the act of coupling with a counterpart connector, and means operating automatically to relieve the connector of the resisting force of said device after the counterpart connectors are coupled and the force exerted through the connectors exceeds the force required to effect the coupling of said connectors.

3. The combination with a train pipe connector, of a member movable laterally with respect to the connector and engaging a cam face associated with said connector and disposed to oppose relative longitudinal movement of the connector through engagement of the cam face with said member, and a spring pressing said member into engagement with said cam face, to thereby oppose movement of said connector with a force in excess of the force required to effect the coupling of said connector with a counterpart connector.

4. The combination with a train pipe connector, of means for yieldingly resisting rearward movement of said connector comprising a member movable laterally with respect to the connector and engaging a rearwardly facing projection associated with the connector and a spring pressing said member into engagement with said face to thereby oppose movement of said connector with a force in excess of the force required to effect the coupling of said connector with a counterpart connector.

5. The combination with a car coupler and a train pipe connector movably supported by said car coupler and means for opposing movement of said connector relative to the car coupler comprising a member movable laterally with respect to the connector and normally engaging a rearwardly facing projection associated with the connector and a spring for pressing said member into engagement with said projection to thereby oppose movement of said connector with a force in excess of the force required to effect the

coupling of said connector with a counterpart connector.

6. The combination with a car coupler and a train pipe connector movably supported by said car coupler and means for opposing movement of said connector relative to the car coupler comprising a member movable laterally with respect to the connector and normally engaging a projection associated with the connector and a spring for pressing said member into engagement with said face, said member being forced out of engagement with said projection when the pressure acting through the connector and tending to move the connector relatively to said member, exceeds the force required to effect the coupling of said connector with a counterpart connector.

7. The combination with a train pipe connector adapted to automatically couple with a counterpart connector when two cars are brought together, a spring, and a member movable laterally with respect to the connector and urged into engagement with a rearwardly facing projection associated with the connector to yieldingly oppose rearward movement of said connector, said member being moved out of engagement with said projection when the pressure exerted through the connector exceeds the pressure required to effect the coupling of counterpart connectors.

8. The combination with a train pipe connector adapted to automatically couple with a counterpart connector when two cars are brought together, and a spring for opposing rearward movement of said connector, a member movable laterally with respect to the connector and engaging a rearwardly facing projection associated with the connector, and a spring acting on said member for pressing said member into engagement with said projection to oppose rearward movement of said connector in such manner that the force opposing rearward movement of the connector exceeds the force required to effect the coupling of said connector to the counterpart connector.

9. The combination with a fluid pressure train line connector adapted to automatically couple with a counterpart connector upon the coming together of two cars, of a projecting portion on said connector, and a member laterally movable and longitudinally rigid with respect to the connector and engaging said portion and positioned to yieldingly oppose rearward longitudinal movement of said portion and thereby said connector.

10. The combination with a fluid pressure train line connector adapted to automatically couple with a counterpart connector upon the coming together of two cars, of a projecting cam face carried by said connector, and a member laterally movable and longitudinally rigid with respect to the connector and

engaging said face and positioned in the path of rearward longitudinal movement of said face to yieldingly oppose rearward longitudinal movement of said face and thereby said connector.

5 In testimony whereof I have hereunto set my hand.

CLYDE C. FARMER.
